CLAIM

The portable dermal freezing unit, as shown and described.

DESCRIPTION

FIG. 1 is a perspective view of a portable dermal freezing unit according to the present invention;

FIG. 2 is an elevation front view of the portable dermal freezing unit of FIG. 1, the rear view being identical thereto;

FIG. 3 is an elevation side view of the portable dermal freezing unit of FIG. 1, the opposite side view being identical thereto;

FIG. 4 is a top plan view of the portable dermal freezing unit of FIG. 1; and,

FIG. 5 is a bottom plan view of the portable dermal freezing unit of FIG. 1.
